CLAIM

The ornamental design for a basket for a vehicle, as shown and described.

DESCRIPTION

FIG. 1 is a perspective view of a basket for a vehicle showing our new design;
FIG. 2 is a top view thereof;
FIG. 3 is a bottom view thereof;
FIG. 4 is a first side view thereof;
FIG. 5 is a second side view thereof;
FIG. 6 is a rear view thereof;
FIG. 7 is a front view thereof; and,
FIG. 8 is a cross-sectional view of a portion of the basket along line 8-8 in FIG. 2.
The broken lines in the figures are included for the purpose of illustrating portions of a basket for a vehicle or its environment and form no part of the claimed design.
